UNITED STATES PATENT OFFICE

DANIEL S. BELDEN, OF LOS ANGELES, CALIFORNIA, ASSIGNOR TO FILTROL COMPANY OF CALIFORNIA, OF LOS ANGELES, CALIFORNIA, A CORPORATION OF CALIFORNIA

PROCESS OF DISTILLING AND PURIFYING FATTY MATERIALS

Application filed May 20, 1929. Serial No. 364,455.

This invention relates to a process of distilling free fatty acids, particularly oleic, palmitic and stearic acids or mixtures of them, from mixtures of free fatty acids, or 5 mixtures of fixed fats with free fatty acids.

Among the objects of the invention is the simultaneous decolorization, purification and distillation of the fatty materials. Another object is the avoidance of the production of large amounts of iso-oleic or hydro- 10 stearic acids, such as may occur in distillation processes using direct superheated steam.

Briefly stated, my process comprises distilling the fatty acids or the like from an acid-proof still while bubbling through them a lively stream of an inert gas, such as carbon dioxide or nitrogen. Experience has shown that steam is not entitled to be called 15 inert. At the same time, the acids are brought into contact with an adsorbent, preferably of the acid-activated clay type. Such adsorbent may either be contained within the still or may be contained in a 20 tower or dephlegmator so that the acids may be acted upon while they are in the vapor phase. The distillation is preferably carried out under as high a vacuum as possible, but permissibly under atmospheric pressure 25 when fatty acids only are being distilled.

In order to carry out my process wherein the adsorbent is in contact with the liquid fatty material during distillation, I may make use of an apparatus of the kind shown 30 in Fig. 1, which is a side elevational view and is more or less diagrammatic.

For distillation with contact in the vapor phase with the adsorbent, I may use the apparatus shown in Fig. 2, which is also a side 35 elevation, also somewhat diagrammatic.

In both figures, 10 represents the body of the still, 11 its residue discharge pipe, 12 a cleaning manhole, 13 a liquid level gauge, 40 14 a vacuum-breaking valve, 15 a pressure gauge, 16 a thermometer, 17 an inlet pipe for fatty material, 18 a vapor outlet pipe having therein a sight glass 19, and 20 a supply pipe for inert gas, said pipe extending almost to the bottom of the still and terminating in a gas-distributing ring 21. The

still is provided with a steam jacket, not shown, or equivalent heating means.

Inert gas may be supplied to the still from a cylinder 22 of compressed gas, which is connected to the pipe 20 at 23. A check 55 valve 24 is provided in the pipe 20 behind the point 23 to prevent flow of gas in an undesired direction. The pipe 20, before it enters the still, passes through a heater 25, containing a steam coil 26 or equivalent 60 heating means. The heater 25 and the remainder of the pipe 20 are preferably heat insulated up to the point where that pipe enters the still.

In Fig. 1, the vapor exit pipe 18 of the 65 still connects with an air condenser 27 of the type which is conventional for this kind of work, it consisting of a number of vertical lengths of pipe connected by return bends 28. The end of the last vertical pipe 70 is connected by means of a pipe 29 to a vacuum pump 30. To the middle of the lower return bends 28 there are connected an equal number of condensing coils 31, one 75 to each bend. The coils are vertically arranged within a cooling box 32 which is provided with a cooling water inlet 33 and outlet. A water level may be maintained about coils 31 or not, as preferred. The lower ends of the coils 31 are each connected 80 to a manifold 34 and are each provided with control valves 35. One or more receivers 36 are coupled to the manifold 34 and are provided with valves 37.

The vacuum pump 30 exhausts into a 85 pipe 38 in which there is a three-way valve 39, through which the pump may exhaust either to the atmosphere or into a storage reservoir 40 for inert gas. A compressor 41 is adapted to take gas from the reservoir 90 and to return it to the still through the pipe 20.

The apparatus shown in Fig. 2 is different from that of Fig. 1 only in that a vapor refining column 50 is interposed between the 95 still and the air condenser. For this purpose a straight vertically-disposed pipe 51, suitably heat insulated, leads from the still to the bottom of the column 50. Within the column 50, a plurality of shelves 52 extends 100

completely across. They are preferably made of coarsely porous carborundum or alundum, or for such materials may be substituted perforated metal shelves having cloth thereon. Resting on the carborundum or cloth is a layer of adsorbent clay not more than two inches in thickness and preferably only about $\frac{3}{4}$ inch thick. The number of such shelves is to be governed by the kind of material worked upon, the efficiency of the bleaching material and other factors, but will ordinarily be from four to ten. Any desired number may be used.

The top shelf has above the layer of adsorbent a protecting porous plate 53 which is provided to prevent particles of the adsorbent from being carried over into the condenser.

The bottom of the column is preferably made conical and provided with a drip pan 54 having a central opening 55. Connected thereto is an outside return pipe 56 leading to the still, to provide for return of condensate.

In operating the apparatus of Fig. 1 in the purification of fatty material in the liquid phase, one proceeds as follows: From 5% to 20% of adsorbent clay by weight of the fatty material to be distilled (in this case assumed to be free fatty acid) is charged into the still. The melted fatty material is then run in through the pipe 17. The still is then heated and the vacuum pump 30 is operated to exhaust the air within the apparatus to the atmosphere through the three-way valve 39. After a high degree of vacuum has been obtained the valve 39 is turned to exhaust any remaining gas into the storage reservoir 40. The valve 24 is then closed if manual operation thereof is required, and inert gas is allowed to run into the pipe 20 from the cylinder 22. Carbon dioxide or nitrogen are the gases preferred for this purpose. Steam is admitted to the heating coil 26 to preheat the gas supply. A lively but not violent stream of gas is supplied through the pipe 20 to the now boiling contents of the still which are continuously kept under reduced pressure.

The compressor 41 is started after the valve 24 is again opened and the supply of gas from the cylinder 22 moderated as distillation proceeds and more recovered gas is supplied by the compressor 41.

The distilling temperatures should be the lowest at which the material under treatment distills freely. For crude stearic acid this range is about 450° F. to 480° F.

As the adsorbent, a sulphuric acid-activated clay of the smectite or bentonite type is preferred, although fuller's earth of good quality can be used. By far the best results are obtained with activated clays, however. A proportion of decolorizing carbon may be added to the clay if desired, but is seldom

necessary. I prefer to use the acid-activated clay known commercially as "Filtrol". It is made by a process somewhat similar to that disclosed by Prutzman in U. S. Patent No. 1,397,113.

The remainder of the distillation, including separation of fatty acids from each other or from fixed fat, may be carried out by any skilled person in possession of the above directions, the condensing features of the process being entirely conventional. The residue left in the still will be found to be a loose powder, easily removed.

In using the apparatus of Fig. 2, the amount of adsorbent to be distributed on the shelves or plates may range from 1% to 10% by weight of the fatty material to be distilled. Care should be taken to distribute it evenly on the shelves. It is to be understood that fresh or revivified adsorbent will usually have to be employed for each batch distilled. The carborundum plates will usually require washing with benzine or other fat solvent after a run. Monel metal and bronze are among the suitable materials, from which the still may be made.

The distillates will be found to be practically waterwhite and of exceptional freedom from unsaponifiable matter and iso-oleic or hydro-stearic acids.

Example, using apparatus of Fig. 1,—

Five hundred pounds of commercial free fatty acids, mainly palmitic and stearic, with 5% by weight of "Filtrol", acid-activated clay, are placed in the Monel metal still. The temperature is raised gradually, the fatty acids beginning to distil as low as 350° F. The mass is constantly agitated by the injection into it of CO₂ heated not to exceed 500° F. The amount of gas injected is not critical but is sufficient to give lively agitation of the still contents. The moisture present in the fat is removed by the action of the stream of gas before the distillation of fatty acid actually begins. The presence of moisture in fatty material during actual distillation, as in the case of steam distillation, has been found to be injurious. Distillation is continued below 500° F. until the mass in the still is completely dry and powdery. The recovery of light colored free fatty acid in the condenser may be as high as 98%. By the term "inert gas" as used in the specification and claims, I exclude both hydrogen and steam, neither of which is strictly inert.

I claim as my invention:

1. A process of recovering fatty acids from fatty material containing same which comprises: adding an active decolorizing agent to said material; subjecting the mixture so produced to sufficient temperature to cause the fatty acids to distill off; agitating the mixture with an inert gas during said distillation; and condensing said fatty acids.
